US00D840384S

(12) **United States Design Patent** (10) **Patent No.:** **US D840,384 S**
(45) **Date of Patent:** **** Feb. 12, 2019**

(54) **ELECTRONIC DEVICE**

(71) Applicant: **Samsung Electronics Co., Ltd.**, Suwon-si (KR)

(72) Inventor: **Junyong Song**, Seongnam-si (KR)

(73) Assignee: **Samsung Electronics Co., Ltd.**, Suwon-si (KR)

(**) Term: **15 Years**

(21) Appl. No.: **29/596,234**

(22) Filed: **Mar. 7, 2017**

(30) **Foreign Application Priority Data**

Nov. 18, 2016 (KR) 30-2016-0055503

(51) **LOC (11) Cl.** **14-03**

(52) **U.S. Cl.**

USPC **D14/248**

CLAIM

I claim the ornamental design for an electronic device, as shown and described.

DESCRIPTION

FIG. 1 is a front perspective view of an electronic device showing my new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof; and,

FIG. 8 is a rear perspective view thereof.

The broken lines in the figures depict environmental subject matter and form no part of the claimed design.

1 Claim, 6 Drawing Sheets
